UNITED STATES PATENT OFFICE.

WILLIAM TEVENDALE, JR., OF PATERSON, NEW JERSEY.

GAS-COCK.

SPECIFICATION forming part of Letters Patent No. 776,816, dated December 6, 1904.

Application filed June 9, 1904. Serial No. 211,779. (No model.)

To all whom it may concern:

Be it known that I, WILLIAM TEVENDALE, Jr., a citizen of the United States, residing in Paterson, in the county of Passaic and State of New Jersey, have invented certain new and useful Improvements in Gas-Cocks; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to gas-cocks such as are used on gas stoves or ranges; and it has for its object to provide a simple and readily-operated gas-cock of this nature which when turned to the closed position will be automatically locked there, thus preventing the accidental flow of gas after the same has once been turned off.

My invention will be found fully illustrated in the accompanying drawings, wherein—

Figure 1 is a view in front elevation of the improved gas-cock. Fig. 2 is a side view thereof. Fig. 3 is a plan view showing the valve in horizontal section, taken just above the valve-casing; Fig. 4, a view similar to Fig. 3, except the valve is shown in the open instead of the closed position as in Fig. 3; and Fig. 5 illustrates certain details of the invention.

In said drawings, *a* designates the service-pipe, to which is attached the usual fitting, shown in the first four figures of the drawings and comprising a shell or valve-casing *b*, having a threaded part *c*, whereby the fitting is attached to the pipe *a*, and a nozzle *d*, provided with the usual jet-piece *e*. The flow of gas through the bore *f*, formed in the threaded part *c* and nozzle *d*, is controlled by the usual conical valve *g*, carrying at its upper end, at right angles thereto, a handle *h*. The valve *g* is limited to move only through a quarter of a revolution by a fixed stop-pin *i*, which works in a segmental recess *j*, formed in the shell *b* where the valve projects out at the top from the latter. When the valve is in the closed position, this stop-pin *i* stands at the right-hand end of the recess *j* as the parts are seen in Fig. 1.

k is a longitudinally-retractile stop-pin ar-

ranged radially in the valve *g* in such position that when the stop-pin *i* stands as shown in Figs. 1 and 3 said stop-pin *k* will stand at the left-hand end of the recess *j*. When the stop-pin projects out of the bore *l* in the valve in which it is mounted, it and stop-pin *i* prevent movement of the valve in either direction; but if stop-pin *k* is withdrawn completely into bore *l* then the valve may be turned to the left to permit the port *m* of the valve to come into alignment with the bore *f* aforesaid.

Stop-pin *k* is controlled as follows: *n* is a spindle arranged in an axial bore *o* in the valve *g* and held true therein by enlargements *p* and *q*, forming bearing-pieces. *r* is a pin projecting downwardly from bearing-piece *q* eccentrically with reference to the longitudinal axis of the spindle, the same being received by a notch *s*, cut in the side of the stop-pin *k*. It will thus be seen that when the spindle turns it will force the stop-pin *k* either in or out, according to the direction of turning said spindle. The spindle is normally turned so as to force the stop-pin out by a spiral spring *t*, which is coiled about the spindle and has its upper end received by a notch *u*, formed in the top of the valve *g*, and its lower end projecting into a hole *v* in the bearing-piece *q*. In order to turn the spindle against the tension of the spring, the spindle carries at its upper end a disk-shaped milled head *w*, which may be conveniently grasped by the thumb and forefinger of the operator. The spindle is kept from upward displacement by a set-screw *x*, which is screwed into the side of the valve and has its point end tapered or sharpened and adapted to enter a correspondingly-shaped groove *y*, formed annularly in the bearing-piece *q*. Assuming that the valve is in the position shown in Figs. 1, 2, and 3, where it is locked in the closed position, it is unlocked for turning it to the open position by turning the milled head *w* against the tension of the spring *t* until the stop-pin *k* is withdrawn completely into its bore *l*. When the valve is again closed and as soon as the stop-pin *k* is freed by having its outer end completely uncovered at the recess *j*, said stop-pin snaps outwardly automatically, so as to lock the valve closed.

It is a feature of no little importance, in-

volving convenience and facility in operation, that the operating part *w* is arranged with its axis coincident with the axis of the valve *g* and that the handle of the valve is one which 5 projects laterally from the valve, for the device can thus be operated easily by one hand, the second, third, and fourth fingers grasping the handle, while the thumb and the first finger manipulate the part *w*.

10 Having thus fully described my invention, what I claim as new, and desire to secure by Letters Patent, is—

15 The combination of a valve-casing, a rotary valve arranged in said casing, said valve having an axial bore, a longitudinally-movable stop-pin arranged in the valve transversely thereof and adapted to protrude therefrom, said valve-casing having a recess adapted to receive the protruding portion of said stop-

pin, a rotary spindle arranged in said bore 20 and having enlargements at its ends forming bearings for said spindle in the bore, a spiral spring coiled about said spindle between the enlargements and having one end secured in said casing and the other end in one of said 25 enlargements, an eccentric-pin projecting longitudinally from said spindle, said stop-pin having a lateral notch receiving said pin, and means for normally retaining said spindle in the valve with its pin engaged in the notch of 30 the stop-pin, substantially as described.

In testimony that I claim the foregoing I have hereunto set my hand this 6th day of June, 1904.

WILLIAM TEVENDALE, JR.
